CLAIM

The ornamental design for a lighting control faceplate, as shown and described.

DESCRIPTION

FIG. 1 is a front elevational view of a lighting control faceplate showing our new design, the rear being unornamented;

FIG. 2 is a right side elevational view thereof, the left side elevational view being a mirror image thereof;

FIG. 3 is a bottom plan view thereof, the top plan view being a mirror image thereof; and,

FIG. 4 is an isometric perspective view thereof.

The broken line showing of a switch housing in FIGS. 2-4 is for illustrative purposes only.
